UNITED STATES PATENT OFFICE.

ALVIN J. ESHENBAUGH, OF SHAMROCK, OKLAHOMA.

ATTACHMENT FOR WELL-DRILLS.

1,305,703.

Specification of Letters Patent.

Patented June 3, 1919.

Application filed July 30, 1918. Serial No. 247,414.

To all whom it may concern:

Be it known that I, ALVIN J. ESHENBAUGH, a citizen of the United States, residing at Shamrock, in the county of Creek and State of Oklahoma, have invented new and useful Improvements in Attachments for Well-Drills, of which the following is a specification.

This invention relates to an attachment for well drills, contemplating particularly the provision of means for rewinding the cables used in various drilling operations back onto the spools on which they are originally wound for transportation.

The various cables used in drilling operations, such as the drill cable, torpedo measuring line or cable, etc., are initially wound upon supply spools or reels, from which they are removed and applied to the bull wheel, torpedo or measuring line reel, etc., for use in the drilling work. After the well is drilled the cables are again rewound upon the supply spools or reels for convenient transportation to the point where the next well is to be drilled.

The object of my invention is to provide means in the form of an attachment whereby a supply spool or reel may be driven from the band wheel of the drill rig for the purpose of rewinding the drill or other cable thereon.

Another object is to provide means whereby a small spool or reel may be directly rotated from the band wheel for rewinding a shorter or smaller cable, such as a torpedo or measuring line, upon its spool.

The invention consists of the features of construction, combination and arrangement of parts, hereinafter fully described and claimed, reference being had to the accompanying drawings, in which:—

Figure 1 is a side elevation of so much of a drilling apparatus as is necessary to illustrate the invention, showing the attachment employed, for rewinding a main cable upon its supply spool.

Fig. 2 is a perspective view of the drive pulley which is applied to the crank shaft of the band wheel.

Fig. 3 is a perspective view of the driven pulley which is mounted upon the supply spool or reel.

Fig. 4 is a view, partly in elevation and partly in longitudinal section, of the supply spool or reel with the driven pulley mounted thereon.

Fig. 5 is a top plan view of the band wheel and its shaft, showing the use of the drive pulley as a support for a spool or reel on which a cable is to be wound.

60

Fig. 6 is a side elevation of the same.

Fig. 7 is a vertical transverse section through the spool or reel shown in Figs. 5 and 6 and through the drive pulley.

Referring now more particularly to the drawings, 1 designates the band wheel of a drilling apparatus; 2 the crank shaft on which it is mounted, said shaft being provided at one end with a crank arm 3 for communicating motion to a walking beam or other drill-tool actuating part of the apparatus; 4 a band or belt by which the band wheel 1 is driven from the motor or engine of the drilling apparatus; and 5 the bull wheel or other wheel or drum on which a working cable 6 is wound in the use of the apparatus. This cable 6 may be the drill line cable, or other cable, used in the various drilling operations. For the purpose of distinguishing the bull wheel or other drum or spool of the drill mechanism from the supply spool or reel, the said wheel, spool or reel 5 may be termed a working spool or reel. It is, of course, to be understood that, so far as the present showing is concerned, to illustrate the mode of use of the present invention, the reel 5 may be either the bull wheel, the measuring line reel, the torpedo line reel, or any other working spool or reel of the drilling apparatus, and the cable 6 may represent any of the cables commonly employed.

7 denotes a supply drum or spool on which the cable 6 is initially wound, for transportation from the factory to the drill operator, 95 and which is commonly employed by the drill operator to receive the cable, which is wound thereon from a working spool after the drilling operation is completed, to enable the cable to be removed from the drilling apparatus and shipped to the next point of use. This spool or reel 7 is shown mounted upon a shaft 8 journaled in suitable bearings 9 upon a frame work 10, which may be a part of the frame work of the drilling apparatus, whereby said spool or reel is rotatably supported for the purpose of unwinding the cable 6 therefrom onto a working spool or reel and afterward rewinding the cable from said working spool or reel 110 back upon the supply spool or reel.

The object of my invention is to provide

means whereby the supply spool or reel 7 may be driven from a working part of the drill mechanism, in this instance the shaft 2 of the band wheel 1, for the purpose of 5 winding the cable 6 from the working spool or reel back upon said supply spool or reel. To this end I provide a grooved drive pulley 11, the inner flange of which is provided with an attaching arm 12 having openings 10 13 formed therein for the passage of bolts or other fastening members, the hub 14 of said drive pulley being provided with a bore or passage 15 for a purpose hereinafter described. The arm 12 is employed for the 15 purpose of fastening the pulley 11 upon the crank arm 3 of the band wheel shaft 2, so that the axis of the pulley 11 will be in alignment with the axis of said shaft, for the purpose of properly transmitting motion to 20 a drive belt or cable 16. The arm 12 is fastened to the crank shaft arm 3 by means of bolts 17 which pass through the openings 13 in the arm 12 and through corresponding openings in the arm 3.

25 For the purpose of driving the spool or reel 7 from the pulley 11 by means of the belt 16 I also provide a driven pulley 18 for application to one end of the spool 7. This pulley is in the form of a peripherally 30 grooved annulus, adapted to fit about one end of the shaft 8 and having an inner rim portion 19 of slightly increased diameter with respect to its outer rim portion and flat-surfaced to bear against the adjacent 35 end of the spool 7. Openings 20 are provided at intervals in this rim portion 19 for the passage of nails or other suitable fastenings 21 to secure the pulley 18 in position.

In the use of the rewinding attachment, 40 it is to be understood that after the drilling operation is completed and it is desired to rewind a working cable 6 from a working spool or reel 5 back onto the supply spool or reel 7, the spool or reel 7 is mounted in 45 proper juxtaposition relative to the spool 5 and the drive belt or cable 16, which is preferably crossed, arranged to engage the pulleys 11 and 18, so that when the band wheel 1 is driven from the motor of the drilling 50 apparatus the spool 7 will be rotated to wind the cable 6 thereon. For this purpose, the free end of the cable 6 is passed over suitable guide pulleys 22 on the drilling apparatus and led from the spool 5 to the spool 7 55 to which it is suitably fastened, so that in the rotation of the drum 7 the cable will be unwound from the spool 5 and onto the spool 7, after which the opposite end of the cable may be properly secured in position. The cable will thus be disconnected 60 from the drilling rig and may be conveniently shipped to the next point for use. It will, of course, be understood that the pulley 11 may be disconnected from the crank arm 12 after each rewinding operation and until 65

its use is again required, and that the pulley 18 may be applied to the spool 7 for use when required and afterward removed.

It is desirable to provide a means whereby a short cable, such as a measuring line or torpedo line, may be conveniently rewound upon its spool or reel or lowered for use, or rewound upon a supply reel or spool while one of the longer working cables, such as the drilling line, is being rewound from the 70 bull wheel onto its supply reel. To this end I provide means whereby a small reel, such as a torpedo or measuring line reel 23, may be supported directly upon the crank shaft 2 by means of the pulley attachment 11. As 75 stated the pulley 11 has its hub 14 provided with an opening 15. Through this opening may be passed the threaded end 24 of a shaft 25 on which the reel 23 is mounted, the opposite end of said shaft being provided with a 80 head 26 to bear against one side of said reel. The threaded end 24 of the shaft projects sufficiently beyond the opposite side of the reel to be passed through the opening 15 in the hub 14 of the pulley 11 and to receive a 85 clamping nut 27 whereby it may be fixed in adjusted position. By slackening this nut the drum 23 may be free for rotation on the shaft 25 to pay out, let down or unwind the cable 28, and by tightening the nut the drum 90 may be clamped against the pulley 11 and fixed thereto with the shaft 25, so that the said drum will rotate with the shaft 2 for the purpose of winding up the cable or rewinding 95 it from a working spool or reel onto the 100 drum or reel 23. A convenient means is thus provided for letting down or lowering a torpedo line or measuring line into a well, winding up the same, or rewinding the line from its working spool or reel onto a supply 105 spool or reel for storage or shipment.

Having thus fully described my invention, I claim:

1. In a cable rewinding attachment for well drills, the combination of a shaft having a crank arm, a band wheel mounted on said shaft, a working reel, a supply reel, a drive pulley mounted upon the crank arm of the crank shaft, a driven pulley mounted upon one side of the supply reel, and a belt connecting said pulleys whereby a cable may be unwound from the working reel and onto the supply reel.

2. In a cable rewinding attachment for drilling apparatus, the combination of a crank shaft having a crank arm, a band wheel mounted on said shaft, a working spool or reel, a supply spool or reel mounted in parallel relation thereto, a drive pulley having its axis arranged in line with the axis of the crank shaft and provided with an arm extending therefrom and fastened to the crank arm of the crank shaft, a driven pulley secured upon one end of the shaft of the supply reel, and a belt connecting said 130

pulleys whereby a cable may be unwound from the working spool and wound onto said supply reel.

3. In a device of the character described, a crank shaft having a crank arm, means for driving said shaft, and a pulley having an arm extending therefrom and adapted for attachment to the crank arm of the crank shaft, to dispose its axis in line with the axis of the crank shaft.

4. In a device of the character described, a crank shaft having a crank arm, means for

driving said shaft, a grooved pulley having a hub provided with a transverse passage, said pulley having its inner flange or rim 15 provided with an arm extending therefrom at right angles to its hub, whereby the pulley may be secured to the crank arm of the crank shaft to dispose its hub in line with the axis of said shaft and in spaced relation 20 to the crank arm of the shaft.

In testimony whereof I affix my signature.

ALVIN J. ESHENBAUGH.
